NICHOLAS S. VEDDER AND FRANCIS RITCHIE, OF TROY, NEW YORK
ASSIGNORS TO WILLIAM RESOR & CO., OF CINCINNATI, OHIO.

Design No. 2,990, dated March 31, 1868.

DESIGN FOR A COOK'S STOVE.

The Schedule referred to in these Letters Patent and making part of the same.

TO ALL WHOM IT MAY CONCERN:

Be it known that we, NICHOLAS S. VEDDER and FRANCIS RITCHIE, of the city of Troy, in the county Rensselaer, and State of New York, have jointly invented or produced a new and original ornamental Design for Cooking-Stoves, of which the following is a full, clear, and exact description, reference being had to the accompanying photograph of a cooking-stove having our said ornamental design.

The distinguishing feature of our said design consists in the formation and arrangement of a central compound ornament, A, and a ribbed surface, B, on the panels or plates, and angular strap-hinges, C, on the door of a cooking-stove, so as to appear as represented in the aforesaid photograph.

What we claim as our invention or production, and desire to secure by Letters Patent, is—

The design for cooking-stoves, herein set forth and shown.

In testimony whereof, we hereunto set our hands, this 1st day of February, 1868, at Troy, New York.

NICHOLAS S. VEDDER,
FRANCIS RITCHIE.
